CLAIM

The ornamental design for the adjustable cross body sling bag, as shown and described.

DESCRIPTION

FIG. 1 is a front perspective view of an adjustable cross body sling bag;

FIG. 2 is a front elevation view thereof;

FIG. 3 is a rear elevation view thereof;

FIG. 4 is a left side elevation view thereof; and,

FIG. 5 is a right side elevation view thereof.

Portions shown as long broken lines depict environmental structure for illustrative purposes only and form no part of the claimed design. Short broken lines on the invention are used to illustrate stitching, which forms part of the claimed design.
